UNITED STATES PATENT OFFICE.

FORREST E. CARDULLO, OF CINCINNATI, OHIO, ASSIGNOR TO THE G. A. GRAY COMPANY, OF CINCINNATI, OHIO, A CORPORATION OF OHIO.

PLANER.

Application filed May 23, 1924. Serial No. 715,276.

My invention relates particularly to planers for large and heavy work, such as are known as frog and switch planers, in which the tools are fed to the work by hand.

5 The object of the invention is to provide novel and improved mechanism, whereby motion may be imparted at will to either or both of the tool holders by hand or by power, in accordance with the wish of the operator.

10 The invention consists of that certain novel construction and arrangement of parts to be hereinafter more particularly pointed out and claimed, in which the above results are attained.

In the drawings:

Figure 1 is a front elevation of a frog and switch planer provided with this mechanism.

20 Figure 2 is a side elevation of the planer with parts broken away to better show the mechanism.

25 Figure 3 is a front elevation of the mechanism in the case on the end of the rail, the front plate and its attached parts being removed.

30 Figure 4 is a section through the mechanism in the case, taken on the line 4—4 in Figure 2.

35 Figure 5 is a perspective view of the clutch throw lever, detent, latch and spring.

40 Figure 6 is a perspective view of the rapid traverse control mechanism separated from the other parts, and without the supporting bearings.

45 Referring to the drawings, 1 and 2 are tools clamped to tool holding members of the usual form which are fastened to slides 3 and 4 which are slidably gibbed to vertical guides formed on the front surfaces of saddles 5 and 6. Saddles 5 and 6 are slidably gibbed to rail 7. To the back of saddle 5 is fixed a nut, not shown, into which is threaded rail screw 8, which is a long threaded shaft journaled at each end in the rail 7. A similar nut on the back of saddle 6 is threaded on a similar rail screw 9.

50 Between the two screws are two parallel splined shafts 10 and 11, called feed rods. To feed rod 10 is slidably keyed a bevel gear (not shown) which drives a suitable train of mechanism, giving vertical motion to slide 3 in the manner commonly employed in planers, or in any other suitable manner. To feed rod 11 is slidably keyed a similar

bevel gear driving a similar train of mechanism giving vertical motion to slide 4. It will be seen that by rotating rail screw 8, horizontal motion will be given to tool 1, the direction of horizontal motion depending on the direction of rotation of the rail screw. By rotating feed rod 10, vertical motion will be imparted to tool 1, the direction of vertical motion depending on the direction of rotation of the feed rod. Similarly rotating rail screw 9 and feed rod 11 will impart motion to tool 2. The various parts so far mentioned may be of the design commonly used for such parts for planers, or of any other suitable design, and do not require further illustration or description.

The mechanism so far described differs from that usually employed in the following particular only. Hitherto only one feed rod has been employed and the vertical movement for both tools has been imparted by this feed rod. This has necessitated the use of mechanism in each head for engaging and disengaging the vertical feed, so that the tools could be moved vertically either independently or simultaneously. The use of separate feed rods in the manner described, avoids this complication, each vertical feed mechanism being permanently geared to its feed rod.

55 Referring now to Figure 4, the feed rod shown is representative of both feed rods and both rail screws, each of which has, at the end nearest the operator, hereinafter termed the right hand end, those parts hereinafter described which are concentric with it.

On the right hand end of each rail screw or feed rod is screwed and pinned driven clutch 12. To the left of clutch 12 and in a counterbored hole in rail 7, is ball thrust bearing 13. Concentric with the rail screw or feed rod, and to the right of clutch 12, are bronze sleeve 13^a, spring 14, and washer 15. To the right of washer 15, and pinned to the rail screw or feed rod, is bronze sleeve 16. The end of the rail screw or feed rod turns in bronze bearing 17, which is held in place in plate 18 by set screw 19. Plate 18 is bolted to case or frame 20, which is adapted to support and protect the various parts which are described herein. Concentric with the rail screw or feed rod is driving clutch 21 having clutch teeth 21^a adapted to engage clutch teeth 12^a on driven clutch 12. This

driving clutch is ordinarily held out of engagement by spring 14 acting against washer 15, which in turn presses against an internal shoulder 21^b formed in driving clutch 21. 5 The distance between shoulder 21^b and the end 21^c of clutch 21 is slightly less than the length of sleeve 16, so that clutch 21 can turn freely, being machined to a running fit on bronze sleeves 13^a and 16. When clutch 10 21 is moved to the left in order to engage clutch 12, it pushes washer 15 over, compressing spring 14. As soon as the pressure is released, spring 14 acts to return clutch 21 to the position shown. 15 On the outer rim of driving clutch 21 are formed gear teeth 21^d by means of which the clutch is revolved. On the outer surface of the clutch are mounted spring 22 and ball thrust bearing 23. The spring is maintained 20 in a partially compressed position by sleeve 24, which is fastened to clutch 21 by screw 25. Acting against ball bearing 23 is a forked clutch shifter 26. When this shifter is moved so as to push ball bearing 23 to the 25 left, clutch 21 is caused to move to the position of tooth engagement. In case the tops of the clutch teeth come together so that clutch can not engage, spring 22 will be compressed. Spring 22 being much stiffer than 30 spring 14, as soon as the driving clutch has rotated sufficiently to bring its teeth opposite the spaces of the driven clutch, spring 22 will force clutch 21 into engagement, against the action of spring 14. 35 Clutch shifter 26 is pinned to shaft 27 having bearings in plate 18, which forms the end of the case on the rail, and plate 28, which forms the front of the case on the rail. To shaft 27 is pinned lever or handle 29, to 40 which is securely fixed detent 30 and knob 31. When handle 29 is pulled down, this detent is engaged by latch 32, and clutch shifter 26 is moved to the left, causing clutch 21 to engage clutch 12. Latch 32 is held in 45 place by flat spring 33, and is pivoted at its upper end on pin 32^b fixed in plate 28. The latch is formed with a button 32^a on its lower end so that it may readily be pressed back by the thumb of the operator. When 50 this button is pressed back the detent is released, spring 14 pushes clutch 21 to the right, carrying with it spring 22 and ball thrust bearing 23, forcing over shifter 26, revolving shaft 27, and raising handle 29 and detent 30 to the position shown in Figure 35. 55 Each of the two rail screws and each of 60 the two feed rods is provided with the associated clutches, sleeves, springs, bearings, clutch shifters, clutch shifter shafts, handles, detents, and latches described above, so that at will, each rail screw or feed rod may be coupled to its corresponding driving clutch. There are therefore, four of each of the 65 above mentioned parts.

The gear teeth of the four driving clutches 21 mesh together so that the clutches are compelled to revolve together. Meshing with the teeth 21^d on one of the driving clutches are teeth 34^e formed on the outer 70 surface of shiftable clutch 34, which is loose on, and concentric with shaft 35, the inner end of which is journaled in the end of the rail, while the outer end is supported by radial thrust bearing 36, housed in bushing 75 37, which is fastened to plate 18 by screw 38. On the end of shaft 35 is keyed gear 39, which meshes with gear 40, keyed to shaft 41, which is manually rotatable by crank 42. To reduce friction, shaft 41 is mounted on 80 ball bearings 43, which are housed in gear cover 44, which is bolted to plate 18. On shaft 35 is mounted mechanically rotatable clutch 45 having teeth on its outer rim, by 85 which it is driven by gear 46, which in turn is driven by a motor through a suitable train of mechanism to be described later.

Clutch 45 is provided with clutch teeth 45^a, adapted to engage clutch teeth, 34^a 90 formed on shiftable clutch 34. On shaft 35, 95 and concentric therewith, is mounted bronze sleeve 47, having shoulder 47^a, against which washer 48 is pressed by spring 49, which is held in place by bronze sleeve 50, fastened to sleeve 47 by screw 51. Shoulder 47^a, sleeve 50, and washer 48 thus maintain 95 spring 49 in partial compression. Washer 48 presses against an internal shoulder 34^b formed in shiftable clutch 34, which may be 100 caused to shift axially on bronze sleeves 47 and 50. To the right of shiftable clutch 34 is manually rotatable clutch 52, which is pinned to shaft 35. Normally clutch teeth 105 formed on the right hand end of clutch 34, engage clutch teeth formed on clutch 52, the clutches being held in engagement by spring 49. Consequently when crank 42 is manually rotated, shaft 41, gear 40, gear 39, shaft 35, clutch 52, and shiftable clutch 34, and the 110 four meshing driving clutches 21, are all caused to rotate.

Should each of the driving clutches be in the position shown in Figure 4, they will 115 revolve freely upon sleeves 13^a and 16 and neither of the rail screws or feed rods will turn. Should, however, the operator pull down one of the handles 29, as for instance the one associated with rail screw 8, the corresponding clutch 21 will be caused to engage its clutch 12, and rail screw 8 will thereby 120 be caused to rotate, moving tool 1 in a horizontal direction. Similarly by pulling down the handle 29 associated with rail screw 9, this screw will be rotatably coupled to the 125 revolving mechanism, and tool 2 will thereby be caused to move in a horizontal direction. By pressing the buttons 32^a formed on the lower ends of the latches 32, the latches will be disengaged from the detents 30 on handles 29, which will permit the clutches to re- 130

vert automatically to the uncoupled position, thus disconnecting the screws from rotative connection with handle 42. In the same way by pulling down the two middle handles 29, 5 the feed rods will be rotatively coupled to handle 42 so that vertical motion may be imparted to the tools.

It is obvious that the direction of vertical or horizontal motion will depend upon the 10 direction of rotation of handle 42. In the case of frog and switch planers I prefer to arrange the rail screws and down feed mechanism so that clockwise rotation of handle 42 will cause the tools to move toward each 15 other, if the rail screws are coupled, or to move downward, if the feed rods are coupled.

Concentric with clutch 34 and mounted loosely thereon is clutch shifter 53 having screw-like cammed faces which engage corresponding cammed faces on bushing 37. 20 By causing clutch shifter 53 to make a partial rotation in either direction, it is caused to move to the left with a screw-like action. This clutch shifter and clutch mechanism is 25 similar in a general way to that described in patent application, Serial No. 490,453, filed by Hunt and Cardullo, August 8th, 1921. When clutch shifter 53 moves clutch 34 to the left it compresses spring 49, uncouples clutch 34 from clutch 52, and moves clutch teeth 34^a into engagement with clutch teeth 45^a on clutch 45. Should the ends of the teeth come in contact, clutch 45 will be forced to the left, pushing over washer 54 30 and compressing spring 55, which are retained in a counterbore hole in rail 7, concentric with shaft 35. Spring 55 is normally maintained in a partially compressed condition by ring 56, which lies in a second counterbored hole in the end of the rail, also 35 concentric with shaft 35, and is held in place by screws 57. As soon as clutch 45 rotates sufficiently so that its teeth come opposite the spaces between the clutch teeth of clutch 34, 40 spring 55 will force clutch 45 to the right, completing the engagement of the clutch teeth. With the parts in this position, the rotation of handle 42 will not cause clutch 34 and clutches 21 to revolve, but the rotation of gear 45 by gear 46 will cause them 45 to revolve. If clutch shifter 53 be returned to its normal angular position, spring 49 will uncouple clutch 34 from clutch gear 45, forcing it into engagement with clutch 52, 50 thus again coupling the train of mechanism to handle 42.

Rail 7 is mounted on two supports 58 and 55 commonly called housings. Between these 60 housings is a brace 60, commonly called the top brace. Mounted on the top brace is a pedestal 61 on which is fastened a reversible electric motor 62. This motor drives by a train of gearing contained in case 63, the horizontal shaft 64. On the end of shaft 64 is keyed bevel gear 65, which meshes with

bevel gear 66, which is on the end of vertical shaft 67. Slidably keyed to vertical shaft 67 is bevel gear 68 which moves vertically with case 20 which is fastened to rail 7. Bevel gear 68 meshes with bevel gear 69 70 which is keyed to horizontal shaft 70 journaled in case 20. To the other end of shaft 70 is keyed gear 46 already mentioned as meshing with clutch gear 45. It will be seen that the rotation of the motor 62 will cause 75 the rotation of clutch 45 through the train of mechanism just described. In case clutch shifter 53 has been rotated until clutch 34 engages clutch 45, the four driving clutches 21 will be caused to rotate by the motor 62 80 instead of by the handle 42, and any rail screw or feed rod operatively connected with its associated driving clutch will thus be mechanically rotated, and move the tool 85 by power.

Motor 62 is supplied with electric current by a drum controller 71 of the usual type, mounted on the back of top brace 60. Projecting from the controller is lever 71^a which rotates the drum to any one of three positions. In mid position as shown in Figure 2, the electric connections are broken and the motor does not rotate. If 71^a is rotated clockwise through an angle of about 30 degrees, electric connections are formed which cause the motor to rotate in one direction. If 71^a is rotated counterclockwise from the mid position through the same angle, electric connections are formed which cause the motor to rotate in the opposite direction. 90 Lever 71^a is connected by connecting rod 72 with lever 73, which is keyed to shaft 74 mounted on the top brace. To the end of shaft 74 is keyed bevel gear 75 meshing with bevel gear 76 which is keyed to the end of vertical shaft 77. Slidably keyed to vertical shaft 77 is sector 78. Meshing with sector 78 95 is one end of rack 79, the other end of which meshes with sector 80 which is fastened to shaft 81. Keyed to shaft 81 are lever 82 and 100 lever 83. Pinned loosely to lever 83 is connection 84 which is also loosely pinned to a lever-like extension 53^a on clutch shifter 53. It will be seen that by moving handle 82, 105 shaft 81 will be caused to make a partial rotation. This movement, transmitted by means of lever 83 and connection 84, will cause the rotation of clutch shifter 53, causing clutch 34 to engage clutch 45, so that 110 the clutch members 21 will be drivable by motor 62. Simultaneously the partial rotation of shaft 81 will cause the movement of sector 80, rack 79, sector 78, shaft 77, bevel gears 76 and 75, shaft 74, lever 73, 115 connection 72, and lever 71^a, which will cause the controller 71 to energize motor 62 causing its rotation in a certain direction. Returning handle 82 to its normal position, will reverse 120 all of the motions described above, uncoupling clutch 34 from clutch gear 45, return- 125 130

ing the controller drum to its neutral position and disconnecting the motor from its source of energy. A movement of handle 82 to the opposite side of its neutral position 82 to the opposite side of its neutral position 5 will again couple clutch 34 with clutch gear 45 and move lever 71^a to the opposite side of its neutral position so that controller 71 will so energize the motor as to cause it to rotate in the opposite direction. It will thus be 10 seen that when handle 82 is in its neutral or mid position, motor 62 will stand still and the screws or rods will be operatively connected to handle 42 for manual operation. A movement of lever 82 will disengage the 15 mechanism from hand lever 42, and operate it by means of the motor 62, the direction of motion being controlled by the direction of motion of handle 82.

It will be seen that the invention provides 20 an extremely convenient means for moving the two tools into any desired position, that they may be moved independently or simultaneously, and that the movement may be effected by hand or by power. Also no attention is required from the operator except 25 to determine which tool he wishes to move, which direction he wishes to move it, and whether he wishes to move it by hand or by power. The mechanism itself is so arranged 30 that all of the necessary actions are accomplished by a single movement, and the operator's attention is not required for such matters as shifting clutches, throwing switches, 35 disengaging feeds, or other similar actions. It will be apparent that the mechanism may be changed in detail without affecting the general principles upon which its action depends. I, therefore, do not wish to confine 40 the invention to the exact form shown, but to include all those forms falling within the scope of the appended claims.

Having thus described my invention, what I claim as new and desire to secure by Letters Patent, is:—

- 45 1. In a planer of the type specified, a shaft, a driven clutch fast to the shaft, a driving clutch loose on the shaft, manually operable means adapted to move the driving clutch into engagement with the driven clutch, a driving member adapted to rotate the driving clutch, means for manually rotating the driving member, and means for mechanically rotating the driving member.
- 50 2. In a planer of the type specified, a shaft, a driven clutch fast to the shaft, a driving clutch loose on the shaft, manually operable means adapted to move the driving clutch into engagement with the driven clutch, a shiftable clutch adapted to rotate the driving clutch, a manually rotatable clutch adapted to have driving engagement with one end of the shiftable clutch, a mechanically rotatable clutch, adapted to have driving engagement with the other end of the shiftable clutch, and means for shifting

the shiftable clutch out of engagement with the manually rotatable clutch and into engagement with the mechanically rotatable clutch.

3. In a planer of the type specified, a shaft, a driven clutch fast to the shaft, a driving clutch loose on the shaft, yielding means tending to hold the driving clutch out of engagement, manually operable means adapted to move the driving clutch into engagement with the driven clutch, a shiftable clutch adapted to rotate the driving clutch, a manually rotatable clutch adapted to have driving engagement with one end of the shiftable clutch, a mechanically rotatable clutch adapted to have driving engagement with the other end of the shiftable clutch, yielding means tending to hold the shiftable clutch in engagement with the manually rotatable clutch, and means for shifting the shiftable clutch out of engagement with the manually rotatable clutch and into engagement with the mechanically rotatable clutch.

4. In a planer of the type specified, an assemblage of parallel shafts, a plurality of driven clutches, one for each shaft, a plurality of driving clutches, one for each shaft, a plurality of manually operable clutch shifters, one for each shaft, and each adapted to operatively connect the conjugate clutches of its shaft, a driving member adapted to rotate the driving clutches, a manually rotatable member for rotating the driving member, a mechanically rotatable member for rotating the driving member, and manually operable means adapted to operatively connect the driving member with either the manually rotatable member or the mechanically rotatable member.

5. In a planer of the type specified, an assemblage of parallel shafts, a plurality of driven clutches, one fast to each shaft, a plurality of driving clutches, one loose on each shaft, means for holding any desired driving clutch in engagement with its driven clutch, a shiftable clutch adapted to impart rotation to all of the driving clutches, a manually rotatable clutch adapted to engage one end of the shiftable clutch, a mechanically rotatable clutch adapted to engage the other end of the shiftable clutch, and means for shifting the shiftable clutch out of engagement with the manually rotatable clutch and into engagement with the mechanically rotatable clutch.

6. In a planer of the type specified, a tool, a feed rod adapted to give motion to the tool, a screw adapted to give horizontal motion to the tool, a driven clutch fast to the feed rod, a driven clutch fast to the screw, a first driving clutch adapted to engage the driven clutch on the feed rod, and having gear teeth formed thereon by means of which it is rotatable, a second

driving clutch adapted to engage the driven clutch on the screw and having gear teeth formed thereon meshing with the gear teeth formed on the first driving clutch, a manually rotatable clutch, a mechanically rotatable clutch, and a shiftable clutch adapted to be driven by the manually rotatable clutch or the mechanically rotatable clutch, and having gear teeth formed thereon adapted to mesh with and drive the teeth formed on the first or the second driving clutches.

7. In a planer of the type specified, an assemblage of parallel shafts, a plurality of driven clutches, one fast to each shaft, a plurality of driving clutches, one loose on each shaft, a plurality of clutch shifters, one for each driving clutch, a plurality of handles, one for actuating each clutch shifter, a shiftable clutch adapted to impart rotary motion to all of the driving clutches, a manually rotatable clutch adapted to have driving engagement with one end of the shiftable clutch, a mechanically rotatable clutch adapted to have driving engagement with the other end of the shiftable clutch, means for shifting the shiftable clutch from engagement with the manually rotatable clutch into engagement with the mechanically rotatable clutch, power means for rotating the mechanically rotatable clutch, means for starting, stopping and controlling the direction of motion of the power means, a hand lever, transmission means operatively connecting the hand lever with the power control means, and transmission means operatively connecting the hand lever with the means for shifting the shiftable clutch.

8. In a planer of the type specified, an assemblage of parallel shafts, a plurality of

driven clutches, one fast to each shaft, a plurality of driving clutches, one loose on each shaft, a plurality of springs, one for each driving clutch, and each tending to hold its driving clutch out of clutch engagement, a plurality of clutch shifters, one for each driving clutch, a plurality of handles, one for actuating each clutch shifter, a plurality of latches, one adapted to hold each handle in position to cause clutch engagement, and to release the handle from this position when pressed away from the handle, a shiftable clutch adapted to impart rotary motion to all of the driving clutches, a manually rotatable clutch adapted to have driving engagement with one end of the shiftable clutch, a first hand lever for rotating the manually rotatable clutch, a spring tending to hold the shiftable clutch in clutch engagement with the manually rotatable clutch, a mechanically rotatable clutch adapted to have driving engagement with the other end of the shiftable clutch, a clutch shifter for shifting the shiftable clutch from engagement with the manually rotatable clutch into engagement with the mechanically rotatable clutch, an electric motor, a controller for starting, stopping, and reversing the electric motor, transmission means for transmitting mechanical power means from the electric motor to the mechanically rotatable clutch, a second hand lever, transmission means for transmitting motion from the second hand lever to the controller, and transmission means for transmitting motion from the second hand lever to the clutch shifter of the shiftable clutch.

FORREST E. CARDULLO.
